UNITED STATES PATENT OFFICE.

HARRY P. STEVENS, OF NEW YORK, N. Y.

BATTERY STEAMER.

Application filed August 27, 1920. Serial No. 406,517.

To all whom it may concern:

Be it known that I, HARRY P. STEVENS, a citizen of the United States, residing at New York city, in the county of New York, 5 State of New York, have invented certain new and useful Improvements in Battery Steamers; and I do hereby declare the following to be a full, clear, and exact description of the invention, such as will enable 10 others skilled in the art to which it appertains to make and use the same.

This invention relates to surface heaters, and more especially to those of that type in which the heating agent is steam; and the 15 particular purpose for which the invention is designed is to heat and soften the composition which is used in storage batteries and the like to seal their parts in place. When such batteries need cleaning and re- 20 pair their parts must be taken out, and in order to accomplish this the sealing composition which is usually of pitch or the like must be softened or melted so that the parts which it covers can be withdrawn from the 25 casing. It is desirable to accomplish such softening of the sealing composition without unduly heating the remaining parts, and the broad purpose of the present invention is to produce a device whereby steam can be applied directly to the top of the composition 30 at a temperature and for a time sufficient to soften it.

One feature of the invention lies in the hood for covering and closely embracing 35 the casing containing the battery, and formation of the mouth of the hood whereby it is adapted to battery casings of various shapes and sizes.

Another feature lies in the provision of 40 openings for permitting the escape of the water of condensation.

Details of several forms of this invention are set forth below and shown in the drawings wherein:

45 Figure 1 is a side elevation partly in section, showing the application of a rubber hood to a storage battery.

Figure 2 is a side elevation of the battery and a partial elevation and section of a 50 hood of fabric.

Figure 3 is a similar view showing a hood having modified forms of water outlet openings.

For illustrative purposes, the battery herein 55 is shown as made up of elements E, each

within its jar J having a top T, and the several jars disposed within a box or casing C and sealed therein by a composition such as pitch P which overlies all the covers or top plates T as seen in Figure 1. This composition is herein called pitch, but whatever its nature it is susceptible to heat when it is desired to soften it to such an extent that the battery elements and jars can be removed as set forth above; and the present invention consists in a device for so treating the pitch.

The numeral 1 designates a pipe to which steam is to be supplied from a source not necessary to show and in quantities and at 70 times under the manual control of the operator. This pipe by preference connects with a nipple 2 disposed substantially at the center of a hood, the same having a body 3 which flares from the nipple to a skirt 4 which surrounds the mouth of the hood and is shaped to approximate the contour of the battery case C at the upper end or mouth of the latter. It is sufficient for the purpose of this specification to assume that the case 80 C is rectangular and of the standard or usual dimensions, and if so the skirt at the mouth of the hood will be a band of relatively the same proportions but of slightly smaller dimensions than the length and 85 width of the mouth of the casing, the purpose being that when the skirt is to be engaged with the casing it must be stretched a little at its mouth and slipped over the same. In order to permit such stretching, 90 the hood, or at least the skirt thereof, must be flexible and elastic; and this is accomplished by making the hood shown in Figure 1 of sheet rubber or a composition containing sufficient rubber to permit it to be 95 elastic. The band constituting the skirt is herein shown as provided with projections or enlargements at intervals, such as knobs 5 attached to or preferably moulded or otherwise made as part of the skirt itself, 100 and when the latter is slipped over the mouth of the casing C these knobs touch the casing as seen at the left of Figure 1, while the spaces 6 between the knobs provide openings for the escape of the water of condensation. The latter forms on the inside of 105 the body of the hood and across the top of the pitch, and will run out through the openings 6, or if it does not run out freely the battery may be tilted to assist.

In the construction shown in Figure 2, the hood is flexible, but fabricated from a non-elastic material, its body 13 being made rather full so as to provide folds 12 radiating from its nipple 2 to its skirt 14, the latter having a bead or casing 15 around its lower edge containing a contractile element such as a coiled spring 17; and as seen at one side of this view the folds are carried 10 down through the skirt so as to leave openings 16 for the escape of steam.

In the construction shown in Figure 3, the body 23, and in fact the skirt 24, may be rigid if the skirt internally be of such shape 15 and size as to fit rather closely around the mouth of the casing C, as will be possible where the hood is to be applied to battery casings of standard size. The material of the body is not essential, but in this case as 20 well as in all cases the body itself may be porous or may be provided with fine perforations to allow the escape of excess steam, and if this porosity were sufficient it would of course permit the escape of the water of 25 condensation. However, I prefer to form outlet openings 26 in the skirt 24, which may be in the shape of holes or slots so disposed that the battery case C does not entirely close them when the hood is placed 30 around it, and these openings may be sufficient in size and number to permit the escape of both the water and the surplus steam.

The description and illustration of these 35 embodiments of the invention are sufficient to show that it may take a variety of forms. The important characteristics are set forth in the claims below, and I reserve the widest latitude as to the details of construction and the uses to which the invention is put.

40 While I refer to the active agent herein as steam, it is obvious that any fluid could be employed whose temperature is sufficient to perform the work desired. It may be that liquids or gases shall be combined with 45 the steam or used as the agent, which possess characteristics especially useful in the melting or otherwise softening of the pitch, and this apparatus could handle such fluid agent and permit the escape of the surplus. There- 50 fore the word "steam" herein should not be construed as limiting the scope of the invention.

What is claimed as new is:

1. The herein described battery steamer 55 comprising a hood having a steam inlet opening, and a mouth adapted to fit around

the battery case, the hood having openings for the outlet of water or condensation.

2. The herein described battery steamer comprising a hood having a central steam 60 inlet opening, a body flaring therefrom to a mouth, and a skirt at the mouth adapted to surround the battery case, the skirt having outlet openings.

3. The herein described battery steamer 65 comprising a hood having a central nipple adapted to be connected with a steam supply pipe, a body flaring from said nipple to the mouth of the hood, a skirt around said mouth having outlet openings, and means 70 for contracting the skirt around the battery case.

4. The herein described battery steamer comprising a hood flaring from a steam inlet opening to a mouth, and having a contractile skirt around said mouth. 75

5. The herein described battery steamer comprising a hood flaring from a steam inlet opening to a mouth, and having a contractile skirt around said mouth provided with 80 outlet openings.

6. The herein described steamer comprising a hood of porous material having a steam inlet opening at one end and a mouth at the other end, and a skirt around said mouth 85

having water outlet openings.

7. The herein described steamer comprising a hood of porous material having a steam inlet opening at one end and a mouth at the other end, and a skirt around said mouth 90 having water outlet openings.

8. The herein described steamer comprising a hood of porous fabric having a steam inlet opening, a body flaring therefrom to its edge and formed in overlapping folds, and 95 means for contracting said edge around the article being steamed and leaving outlet openings between the folds.

9. A hood for steaming articles, the same composed of fabric having a steam inlet, a body flaring therefrom, a skirt at the edge of the body and provided with a bead, and a contractile element within the bead, the body and skirt being formed in overlapping folds 100 whereby they are adaptable to the size and shape of said article.

In testimony whereof, I affix my signature, in the presence of two witnesses.

HARRY P. STEVENS.
